DENTURE BRUSHING DEVICE

Thomas A. Binkley, Wilson, N. C.

Application March 28, 1940, Serial No. 326,491

3 Claims. (Cl. 15—21)

This invention relates to a device for cleaning dentures or the like.

It is particularly aimed to provide a construction having brushes rotatable in opposite directions within a case and operable by a crank or the equivalent from the exterior thereof.

It is further aimed to provide such a construction having a lid or cover capable of opening, which carries one of the brushes in an operative position for rapid meshing and demeshing with respect to the driving gear.

The more specific objects and advantages will become apparent from a consideration of the description following taken in connection with accompanying drawing illustrating an operative embodiment.

In said drawing—

Figure 1 is a plan view of the device;

Figure 2 is a vertical section taken on the line 2—2 of Figure 1;

Figure 3 is a vertical section taken at a right angle to Figure 2, and on the line 3—3 of Figure 1, and

Figure 4 is a horizontal section taken on the line 4—4 of Figure 3.

Referring specifically to the drawing wherein like reference characters designate like or similar parts, a case is provided as at 10, consisting of a lower or container section 11, having a cylindrical upstanding wall 12, and the case also having a lid or cover 13, in the form of a plate or disk, removably positioned but preferably hinged for opening as at 14, on the upper edge of the cylindrical wall 12, such disk or plate 13, preferably having a spring latch 15, whereby it may releasably engage a lug or keeper 16 on the wall 12, to hold the cover or closure against accidental opening.

Within the case a pair of brushes 17 and 18 are provided in opposed relation, adapted for rotation in opposite directions to cleanse a denture disposed therebetween, with the aid of any liquid or other cleaning material contained in section 12 or disposed on the brushes or against the denture.

Each brush 17 and 18 is substantially similar, each having a back 19 of plate or disk form, of wood, Bakelite or any other suitable material. Tufts of bristles, as at 20, extend from each back 19 toward the other back terminating slightly short of contact with each other, so that they will effectively contact the opposite sides of a denture engaged between them. Back 19 is journaled for rotation on a stud 21, fastened centrally to the bottom wall of section 11 and brush 17 is jour-

naled on a stud or spindle 22 fastened centrally to the cover or closure 13. Thus each brush, is rotatable. Each brush has a gear ring 23 fastened thereto in any suitable manner, as by means of screws 24. Said gear rings project laterally beyond the heads 19 and are there provided with series of equidistantly spaced gear holes or perforations 25.

Within the case 10 and at one side thereof, a gear member 26 is disposed for rotation on a horizontal axis, being fixed to the inner end of a crankshaft 27 extending through the wall 12, with the crank 28, located exteriorly thereof for manual engagement and operation. Spacing means 29 and 30 are provided about the shaft 27, 15 interiorly and exteriorly of the case. Said gear 26 has equidistantly spaced peripheral teeth 31 which are engaged or enmeshed with the openings 25.

In operation, the closure 13 is swung open on 20 the hinge 14, carrying the brush 17 to an open position, whereupon the denture or plate or the like is disposed within the case on top of the bristles of the lower brush 18. Thereafter, closure 13 is restored to closed position so that the bristles of the upper brush 17 will engage the denture or plate on the opposite side to the bristles of the other brush. Thereupon the crank 28 may be operated to rotate the gear 26 and the gear rings 23, accordingly rotating the brushes in opposite directions, and effectively cleaning both sides of the denture or plate, with the aid of any cleaning medium contained within the case 12, the bristles 20 or the denture or plate. The denture or plate may thereafter be readily removed upon opening the closure 13. 35

Various changes may be resorted to provided they fall within the spirit and scope of the invention.

I claim as my invention:

1. A denture cleaner of the class described having a case, a closure on said case movable to an open position, brushes between which a denture is disposable for cleaning, one of said brushes being journaled within the case, the other brush 45 being journaled on the inner face of the closure in opposed relation to the first mentioned brush, means operable from the exterior of the case to rotate said brushes in opposite directions, consisting of a gear within the case, and gear means 50 on the brushes enmeshed with said gear, the gear means on the brush of the closure being demeshable with the gear through opening of the closure.

2. A denture cleaner of the class described having a case, a closure on said case movable to an 55

- open position, brushes between which a denture is disposable for cleaning, one of said brushes being journaled within the case, the other brush being journaled on the inner face of the closure 5 in opposed relation to the first mentioned brush, a gear within the case, gear means on the brushes enmeshed with said gear, and a crankshaft journaled in the wall of the case carrying said gear and operable exteriorly of the case.
- 5 10 3. A denture cleaner of the class described having a case, a closure on said case movable to an open position, brushes between which a denture

is disposable for cleaning, one of said brushes being journaled within the case, the other brush being journaled on the inner face of the closure in opposed relation to the first mentioned brush, a gear within the case, and gear rings on the 5 brushes enmeshed with said gear, said rings extending laterally beyond the brushes and provided with equidistantly spaced openings engaged by the teeth of the gear, the ring on the brush of the closure being demeshable with the gear 10 through opening of the closure.

THOMAS A. BINKLEY.
